UNITED STATES PATENT OFFICE.

HERMAN LEINEWEBER, OF SOUTH CHICAGO, ILLINOIS, ASSIGNOR OF ONE HALF TO W. M. BAYNE, OF CHICAGO, ILLINOIS.

PNEUMATIC TOOL.

No. 846,857.

Specification of Letters Patent.

Patented March 12, 1907.

Application filed November 6, 1906. Serial No. 342,179.

To all whom it may concern:

Be it known that I, HERMAN LEINEWEBER, a citizen of the United States, residing at South Chicago, in the county of Cook and 5 State of Illinois, have invented a new and useful Improvement in Pneumatic Tools, of which the following is a specification.

My invention relates to an improvement in valveless pneumatic tools of the class in 10 which a piston confined in a barrel is reciprocated by air-pressure introduced alternately against its opposite ends into chambers contained in the barrel and between which the piston works to hammer a chisel, a riveting, 15 or other tool in its path extending from an end of the barrel; and it relates more particularly to the construction of the piston and that of the barrel of such a pneumatic tool.

The primary object of this invention is to 20 provide a novel construction of valveless pneumatic tool whereby the advantage shall be afforded of a long stroke of the piston without requiring to that end that the proportions of the parts shall be such as to render 25 the dimensions and weight of the implement greater than the conventional size and weight of the ordinary pneumatic tool in the same class.

A further object is to enable the piston to 30 be introduced with either end foremost into place in the barrel, with the advantage of rendering its introduction proof against carelessness on the part of users of the tool, who are liable to insert wrong-end foremost into 35 its barrel a piston which is adapted to be properly introduced therein only with one of its ends foremost.

In the accompanying drawing, Figure 1 is 40 a broken view in elevation, mainly sectional, of a pneumatic tool embodying my improvements; and Figs. 2, 3, 4, 5, and 6 are sections taken, respectively, at the lines 2, 3, 4, 5, and 6 on Fig. 1 and viewed as indicated by arrows.

The barrel shown is of known general 45 form, involving the cylindrical body 7, into one end of which is inserted the tool proper, 8, with a hollow head 9 fastened about the rear end portion and carrying the handle 10 of a usual or any suitable construction, provided with a thumb-lever 11 for controlling the admission of air-pressure into the barrel to work a piston therein, an air-chamber 12 being formed in the forward end portion of the body 7 and the head containing

the larger air-chamber 13, into which projects centrally the hollow boss 14 for cushioning the back stroke of the piston.

The piston 15 is a solid piece of metal, preferably of the cylindrical shape represented and contains near its ends the circumferential feed-grooves 16 and 17. Except at these grooves the piston fits accurately about the interior of the barrel-section 7. It is important for the purposes hereinafter explained that the longer portion of the solid 65 piston extending between the feed-grooves shall be of uniform diameter throughout.

A plurality (preferably three, as shown) of holes forming air-passages 18 are bored at equal intervals apart longitudinally in the 70 wall of the barrel portion 7 to extend from its outer end, where each is closed by a plug (indicated at 19) into the forward air-chamber 12, and each passage 18 contains between its ends a port 18^a, these ports being thus also 75 at equal distances apart about the interior of the barrel. Similarly holes, preferably to the same number as those first named, are bored in said wall to form air-passages 20, extending from the outer end of the wall, 80 where they open into the chamber 13 to points about midway between the two air-chambers, each terminating at its inner end in a port 21, extending laterally into the interior of the barrel, these ports being thus also 85 at equal distances apart about the interior of the barrel. Similar holes, preferably to the same number as those in each of the other sets, are bored in said wall to form air-passages 22, extending from the outer end of the 90 wall, where each is closed by a plug (indicated at 23) to the same depth as the passages 20, where they terminate in ports 24, extending laterally into the interior of the barrel, also at equal distances apart, and from each 95 of these last-named passages at a less depth therein there extends into the interior of the barrel a port 25, like and alining with a port 24. At 26 and 27 are provided exhaust-ports in the barrel. As will be observed, the passages 18 are shown relatively narrow, since less pressure is required in the chamber 12 to return the piston than in the chamber 13 to advance it.

The actuating air-pressure is supplied by 105 way of a passage 28, formed in the barrel-section 9 to communicate at one end with the air-pressure supply (not shown) and near its

opposite plugged end 28^a with a port 29, leading to an air-pressure feed-channel 30, formed in the walls of the barrel-sections 7 and 9 to extend part way about the barrel, as shown in Fig. 2, and from which narrower ports 31 lead each to a passage 22.

As represented in Fig. 1, the piston is at the end of its forward stroke, at which it hammers against the end of the stem of the tool 8, and in reaching which its advance end passes through a guide-bearing 32, which may be formed about the wall of the chamber 12 and is provided at intervals with transverse slots 33 to afford communication between the two parts of the chamber separated by the bearing.

To operate the tool, the actuating air-pressure is admitted to the passage 28 and by way of the port 29 into the channel 30, whence it enters through the ports 31 and 18^a into the passages 18. In that position of the piston the ports 25 of the passages 22 register with the piston-groove 17 and through the latter open at the ports 18^a into the passages 18, through which the air-pressure passes into the chamber 12 and drives the piston backward, exhausting through the ports 26 when the piston clears them in its back stroke. The resultant position of the piston causes it to close the ports 25 and registers its forward groove 16 with the ports 24 of the passages 22 to admit the pressure into that groove, which also then registers with the ports 21 of the passages 20 opening into the chamber 13 to introduce the pressure therein for driving the piston forward, the pressure exhausting through the ports 27 as the piston clears them.

From the foregoing explanation of the operation it will be understood that the passages 22, while the air-pressure supply is open, feed the pressure alternately to the chamber 12, through the ports 25, grooves 17, ports 18^a, and passages 18 and to the chamber 13 through the ports 24, groove 16, ports 21, and passages 20.

My improvements render the construction of the pneumatic tool simple and very durable. The imperforate or solid construction of the piston adds greatly to the durability of the implement, not only because of its inherent strength, but because of its reversibility, whereby when one end is worn with use by hammering the other end may be used for the purpose, thus practically doubling the life of the piston. The pressure-feed grooves 16 and 17 being formed, as they preferably are, at the same distance from the respectively adjacent piston end permit this reversed use, and the end portions and intermediate portion of uniform diameter effectively close communication between the chambers 12 and 13, and the ports are effectively closed by the intermediate portion when it covers them. The function of the

grooves about the piston is to afford communication with the air-pressure supply of the two pressure-chambers alternately through the air-passages in the barrel leading, respectively, to one chamber in one extreme position of the piston and to the other chamber in the other extreme position of the piston.

The features of more particular peculiarity in the construction herein shown and described are the following: The long section of the solid piston between the feed-grooves near its ends alone controls the opening and closure of the ports 25 and 24, by which the driving air-pressure is admitted alternately to the opposite air-chambers 12 and 13. Depending on the relative proximity to each other of the members of each pair of the ports 25 24, the intermediate section of the piston may be relatively longer or shorter than represented; but with these two sets of ports sufficiently close together to cause the rear portion of this section of the piston at the end of the forward stroke of the latter, to cover and thus close the set of ports 24, 90 while the groove 17 registers with the ports 25, and to cause the forward portion of this section of the piston at the end of the back stroke of the latter to cover and thus close the set of ports 25, while the groove 16 registers with the ports 24, the desired long stroke of the piston may be obtained. The described relative disposition about the piston of the ports 18^a, 24, and 25 with the members of each set thereof at equal or substantially equal distances apart is also of importance. Owing to the length required of the solid piston for attaining the desired long stroke, any material pressure of the air exerted through ports and thus laterally against the surface of the section of the piston which closes them would, unless such pressure were uniformly, or substantially so, distributed about it, bind it against the barrel, with the result of impairing the force of the stroke by the ensuing friction. All tendency to such binding is avoided by disposing the members of each set of these ports, consisting of at least three, at equal distances apart about the piston, since thereby the air-pressure exerted laterally against it is uniform from all directions, with the effect of balancing the piston in its movements and rendering the stroke free from undue friction.

What I claim as new, and desire to secure by Letters Patent, is—

1. In a valveless pneumatic tool, the combination of a barrel containing air-chambers in its opposite end portions, an air-pressure-feed passage leading into said barrel and communicating with the supply of actuating air-pressure, air-pressure passages in the barrel-wall leading in opposite directions, respectively, into said chambers; said passages having ports opening into the interior of the bar-

rel and disposed at substantially equal distances apart about the same, and an imperforate reciprocating piston in said barrel working between said chambers and provided near each end with a circumferential pressure-feed groove, with the long section between said grooves of uniform diameter throughout, for the purpose set forth.

2. In a valveless pneumatic tool, the combination of a barrel containing air-chambers in its opposite end portions, an air-pressure-feed passage leading into said barrel and communicating with the supply of actuating air-pressure, air-pressure passages in the barrel-wall leading in opposite directions, respectively, into said chambers, said passages having ports opening into the interior of the barrel and disposed at substantially equal distances apart about the same, and a solid reciprocating piston in the barrel working between said chambers and provided near its ends with circumferential pressure-feed grooves, with the long section between said grooves of substantially uniform diameter throughout, said piston having like end portions and being invertibly insertible and operative in the barrel, for the purpose set forth.

3. In a valveless pneumatic tool, the combination of a barrel containing air-chambers in its opposite end portions, an air-pressure-supply passage in the barrel-wall, pressure-feed passages in said wall leading from said supply-passage to the interior of the barrel, air-pressure passages in said wall communicating with said supply-passages and leading to the forward air-chamber, air-pressure passages in said wall communicating at their inner ends with said supply-passages and leading into the rear air-chamber, ports opening from each set of said air-pressure passages laterally into the interior of the barrel and disposed at substantially equal intervals apart about the same, and a solid reciprocating piston in the barrel working between said chambers and provided near each end with a circumferential pressure-feed groove, with the long section between said grooves of uniform diameter throughout, for the purpose set forth.

4. In a valveless pneumatic tool, the combination of a barrel containing air-chambers in its opposite end portions, an air-pressure-

supply passage in the barrel-wall, a pressure-feed groove formed about the interior of said wall and into which said passage leads, pressure-feed passages in said wall communicating with said groove and provided at their inner ends with ports opening laterally into the interior of the barrel at substantially uniform distances apart about the same, air-pressure passages in said wall communicating with said ports and leading to the forward air-chamber, air-pressure passages in said wall having ports at their inner ends at substantially uniform distances apart about the same and leading at their outer ends to the rear air-chamber, and a solid reciprocating piston in the barrel working between said chambers and provided near each end with a circumferential pressure-feed groove, with the long section between said groove, of uniform diameter throughout, for the purpose set forth.

5. In a valveless pneumatic tool, the combination of a barrel containing air-chambers in its opposite end portions, an air-pressure-supply passage in the barrel-wall, a pressure-feed groove formed about the interior of said wall and into which said passage leads, pressure-feed passages in said wall communicating near their outer ends with said groove and provided with ports at varying depths in them leading into the barrel at substantially uniform distances apart about the same, air-pressure passages in said wall having ports near their inner ends at substantially uniform distances apart about the barrel and registering with the outermost of said first-named ports and leading to the forward air-chamber, air-pressure passages in said wall having ports at their inner ends in the plane of the innermost of said first-named ports and at substantially uniform distances apart about the barrel and leading at their outer ends to the rear air-chamber, and a solid reciprocating piston in the barrel working between said chambers and provided near each end with a circumferential pressure-feed groove, with the long section between said grooves of uniform diameter throughout, for the purpose set forth.
